United States Patent Office.

GEORGE S. MCKENZIE, OF CLEVELAND, OHIO.

Design No. 3,071, dated June 16, 1868.

DESIGN FOR A TRADE-MARK.

The Schedule referred to in these Letters Patent and making part of the same.

TO ALL WHOM IT MAY CONCERN:

Be it known that I, GEORGE S. MCKENZIE, of Cleveland, in the county of Cuyahoga, and State of Ohio, have originated and designed a new Design for a Trade-Mark, of which the following is a full, clear, and exact description, reference being had to the accompanying drawings making part of this specification.

This design consists of a centre-piece, A, representing the back of a shirt, surmounted by a head, and having a diagram for measurement, with reference-letters for the same. Above this diagram in a curved line are placed the words "Forest City," in a suitably-displayed letter, and below the same design A is placed the word "Shirt," in a curved line also, and opposite to the said upper line.

The said words "Forest City" and "Shirt" may be engraved so as to be printed in one or more colors, and the centre-piece in another color, if desired, but the main object being the adoption of the name "Forest City Shirt," together with the design A, aforesaid, as a trade-mark.

What I claim as my invention, and desire to secure by Letters Patent, is—

The design for a trade-mark, as herein set forth and shown.

GEO. S. MCKENZIE.
